CLAIM

The ornamental design for a case for tablet computer, as shown and described.

DESCRIPTION

FIG. 1 is a front perspective view of a case for tablet computer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled region from FIG. 2;

FIG. 10 is a cross-sectional view of the case for tablet computer taken in the direction of line 10-10 of FIG. 4; and, FIG. 11 is a cross-sectional view of the case for tablet computer taken in the direction of line 11-11 of FIG. 4.

The dash-dot broken line circle in FIGS. 2 and 9 delineates a portion of the case for tablet computer that is part of the claimed design and that is shown on an enlarged scale in FIG. 9. The broken lines throughout the drawing figures depict portions of the case for tablet computer that form no part of the claimed design. The broken lines and regions bounded by broken lines form no part of the claimed design.
